CLAIM

The ornamental design for a square tube fence as shown and described.

DESCRIPTION

FIG. 1 is a perspective view of a square tube fence showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of area 9 shown in FIG. 1; and, FIG. 10 is an enlarged view of area 10 shown in FIG. 2.

The dash-dash broken lines depict portions of the square tube fence that form no part of the claimed design. The dash-dot-dash broken lines in FIGS. 1, 9 and 10 denote the boundaries of the enlarged detail views and form no part of the claimed design.

1 Claim, 10 Drawing Sheets
